UNITED STATES PATENT OFFICE.

AUGUST L. REINKE, OF LYONS, IOWA.

FASTENER FOR NECK-YOKES.

SPECIFICATION forming part of Letters Patent No. 739,508, dated September 22, 1903.

Application filed May 16, 1903. Serial No. 157,465. (No model.)

To all whom it may concern:

Be it known that I, AUGUST L. REINKE, a citizen of the United States, residing at Lyons, in the county of Clinton and State of Iowa, have invented a new and useful Fastener for Neck-Yokes, of which the following is a specification.

This invention relates to certain improvements in neck-yokes, and more particularly to novel means for preventing the neck-yoke from becoming accidentally detached from the tongue or pole of a vehicle by the forward movement of the team or from other causes.

The object of the invention is to provide a simple, inexpensive, and efficient device of this character which may be easily and quickly attached to the ordinary pole or tongue of a vehicle and by means of which the neck-yoke is prevented from becoming detached and the tongue falling to the ground should the traces break and the team attempt to run away.

The invention consists in the construction and novel combination and arrangement of parts hereinafter fully described, illustrated in the accompanying drawings, and pointed out in the claims hereto appended, it being understood that various changes in form, proportion, and minor details of construction may be resorted to without departing from the spirit or sacrificing any of the advantages of this invention.

In the accompanying drawings, Figure 1 is a perspective view of a neck-yoke and pole constructed in accordance with my invention, showing the same applied to a team. Fig. 2 is a side elevation of the same, showing in dotted lines the locking-levers in the elevated position. Fig. 3 is a detail perspective view of the supporting-brackets detached.

Similar numerals of reference indicate corresponding parts in all the figures of the drawings.

1 designates the pole or tongue of an ordinary two-horse vehicle, 2 the neck-yoke, and 3 the ring connected to the yoke and which engages the pole or tongue in the usual manner. A guard iron or strap 4 is secured to the pole or tongue, having its intermediate rounded portion projecting beyond the tip of the pole, so as to form a ring or eye 5, to which the neck-yoke strap may be attached or for connection of a lead horse, the lower

leg of the strap being bent to form a stop or holdback 6, adapted to limit the rearward movement of the neck-yoke ring.

55

Secured to the opposite sides of the tongue or pole and at a point adjacent the tip thereof are supporting-brackets 7, each preferably formed of a single piece of metal or other suitable material provided with inwardly-extending flanges 8 and 9, the ends of which are serrated, as shown, to form teeth 10, adapted to be driven in the tongue and support the bracket in position thereon.

60

The opposite ends of the supporting-bracket 65 are cut away, as shown at 11, and pivoted within said brackets by means of a pin or bolt 12, extending through the tongue and coincident openings 13 in said brackets, is a pair of longitudinally-extending parallel locking-levers 14, the free ends of which are provided with downwardly-extending hooks 15, adapted to engage the ring 3 and prevent the neck-yoke from becoming detached from the tongue should the traces break and the team attempt 70 to run away. By having the rear ends of the levers 14 pivoted within the supporting-brackets said levers are free to move upwardly in a vertical plane to permit the neck-yoke ring 3 being passed over the hooked 75 ends thereof and in engagement with the stop 6, the levers dropping by gravity upon being released, causing the hooks 15 to extend below the bottom of the tongue and in position to engage the ring 3 in case of any 80 forward movement thereof.

70

The cut-away portions 11 of the supporting-brackets 7 permit the levers 14 to swing freely on the pin or bolt 12, the upward movement thereof being limited by the flange 8 and the 85 downward movement by the flange 9.

50

In operation when it is desired to attach the neck-yoke to the tongue or pole the levers 14 are lifted until the hooks 15 lie parallel to and in contact with the sides of the pole, as 90 shown in dotted lines in Fig. 2 of the drawings, in which position the neck-yoke ring 3 may be slipped over the end of the tongue and in contact with the stop 6, the hooks upon being released automatically returning 100 to their normal position and preventing the ring from becoming detached and the tongue falling to the ground should the traces break and the team attempt to run away.

90

100

From the foregoing description it will be seen that I have provided an extremely simple and inexpensive device adapted to guard against accident arising from the neck-yoke ring working loose or otherwise becoming accidentally detached from the end of the tongue of a wagon or other vehicle, thereby preventing the tongue from dropping to the ground and wrecking or otherwise damaging the vehicle.

Having thus described the invention, what I claim, and desire to secure by Letters Patent, is—

1. A neck-yoke-attaching device comprising, a pair of supporting-brackets adapted to be secured to the opposite sides of the vehicle-tongue, and locking-levers pivoted within the brackets and adapted to engage the neck-yoke ring.

2. A neck-yoke-attaching device comprising, brackets for securing to the opposite sides of the vehicle-tongue, locking-levers pivoted within the brackets and adapted to engage the neck-yoke ring and means carried by the brackets for limiting the upward and downward movement of the levers.

3. A neck-yoke-attaching device comprising, a pair of brackets provided with inwardly-extending flanges adapted to be secured to the opposite sides of the vehicle-tongue, and lock-

ing-levers pivoted within the brackets and adapted to engage the neck-yoke ring.

4. A neck-yoke-attaching device comprising, brackets for securing to the opposite sides of the vehicle-tongue, said brackets being provided with inwardly-extending flanges having terminal teeth or spurs, and locking-levers pivoted within the brackets and having their free ends provided with downwardly and rearwardly extending hooks adapted to engage the neck-yoke ring.

5. A neck-yoke-attaching device comprising, brackets for securing to the opposite sides of the vehicle-tongue, said brackets being provided with inwardly-extending flanges provided with oppositely-disposed openings or recesses, locking-levers pivoted within the brackets and provided with downwardly and inwardly extending terminal hooks adapted to engage the neck-yoke ring, the flanges on the brackets forming a stop to limit the upward and downward movement of the pivoted levers.

In testimony that I claim the foregoing as my own I have hereto affixed my signature in the presence of two witnesses.

AUGUST L. REINKE.
